(57) **CLAIM**

The ornamental design for an interdental brush, as shown and described.

DESCRIPTION

FIG. 1 is a perspective view of an interdental brush showing my new design;

FIG. 2 is a front view thereof;

FIG. 3 is a side view thereof;

FIG. 4 is an opposite side view thereof;

FIG. 5 is a top view thereof; and,

FIG. 6 is a bottom view thereof.

The uneven-length broken lines represent unclaimed boundaries of the claimed design. The even-length broken lines showing the remainder of the interdental brush represent unclaimed subject matter and form no part of the claimed design.

1 Claim, 4 Drawing Sheets

FIG. 2

FIG. 3

FIG. 4

FIG. 5

FIG. 6
